UNITED STATES PATENT OFFICE.

PERCY L. MARTIN, OF MONROE, LOUISIANA.

DEVICE FOR GATHERING REFUSE.

1,053,418.

Specification of Letters Patent. Patented Feb. 18, 1913.

Application filed March 1, 1911. Serial No. 611,668.

To all whom it may concern:

Be it known that I, PERCY L. MARTIN, a citizen of the United States, residing in Monroe, Ouachita parish, State of Louisiana, have invented a certain new and useful Device for Gathering Refuse, of which the following is a specification.

My invention relates to a device which is adapted to be used for the gathering of refuse for the purpose of destroying or otherwise disposing of the same.

My device is designed particularly for use in gathering or collecting the fallen blossoms, squares and bolls of cotton in cotton fields where the boll weevil is present.

It is known to those who are familiar with the cotton growing industry that in certain parts of the South the boll weevil has made its appearance and whenever it attacks the blossoms, squares, and bolls the latter fall to the ground. It is desirable that such fallen parts should be collected together and destroyed by burning or in some other manner for the purpose of destroying and eradicating the boll weevil.

The device invented by me and which forms the subject of this application has been designed and adapted for use in collecting such fallen parts of the cotton plant, but as already indicated it may be employed for other analogous purposes and uses.

In order that my invention may be more readily comprehended and its uses and advantages be more apparent, I have illustrated one form of a convenient embodiment thereof in the accompanying drawings, but it will be understood that changes in the details of construction within the scope of the claims may be made without departing from my invention.

In the drawings:—Figure 1 is a side elevation of a device embodying my invention; Fig. 2 is a bottom plan view of the same; Fig. 3 is a transverse section on the line 3—3 of Fig. 1; and Fig. 4 is a longitudinal section on the line 4—4 of Fig. 3 the parts being in different relative position with respect to each other.

Referring to the drawings:—1 designates a handle provided with a base plate 2 provided with a boss 3 having a socket 4 in which the lower end of the handle is secured.

The handle may be secured in the socket 4 in any suitable and convenient way, as, for instance, by means of a pin or bolt 5 which extends through the walls of the said

socket and through the inner end of the handle, as is clearly indicated in the drawings.

10 designates pointed pins which are secured in any convenient manner to the said base or support 2. These pins preferably are made of portions of wire pointed as indicated at 11.

Preferably, as is illustrated in Figs. 1 and 4 of the drawings, the pins or pin at the center of the group of pointed pins is longer than the surrounding pins of the group the length of which gradually decreases from the center of the group outwardly. This arrangement is for the purpose of accommodating the points of the pins to the angle at which the device is held when in use, it being desirable that the points of the pins which contact with the ground and with the articles to be collected or gathered up should 75 occupy a plane more or less nearly parallel with the plane of the ground from which such articles are collected and gathered.

It is desirable that the diameter of the pins be small in order that the device may not be too heavy to be conveniently operated. In consequence of their smallness the pins may be bent in use. For the purpose of holding the said pins to a certain extent against bending, I provide a combined guard 85 or stay and cleaner or stripper 12, which is bent or turned in the manner indicated in Figs. 1 and 4 of the drawings so that it forms a shallow inverted cone, the apex of which is located at its center and is substantially coincident with the central pin of the device. As will be observed the guard and cleaner 12 is provided with holes or perforations 13 through which the pins pass.

In order that the plate 12 may cause the 95 cleaning or stripping of the leaves, blossoms, squares or bolls of cotton or other objects from the said pins, it is necessary that there should be relative movement between the same and the guard and stripper or 100 cleaner 12. Such relative movement may be occasioned either by causing movement of the member 12 or by causing movement of the pins themselves with relation to the said member 12. Preferably I cause movement of the cleaner or stripper 12. The mechanism provided for this purpose consists of links 15 (three being shown) which are pivoted at 16 to ears 17 upon the peripheral edge of the plate 12. The upper 110 ends of the said links are pivoted at 18 to the lower end of a sleeve 19 which is adapt-

ed to be moved longitudinally upon the handle 1 by the person who may be using or operating the device.

In order that the sleeve 19 may be held 5 in the position indicated in Fig. 1 of the drawings in which the cleaner or stripper 12 is located at a point adjacent to the base 2, I have provided a bent spring 20 bowed in the manner indicated in Fig. 1 which 10 spring operates to prevent the sleeve 19 from sliding down upon the handle or toward the base 2.

In the use of my device for the purpose 15 of collecting refuse matter of any kind or character, the stripper or cleaner 12 should be held at such distance upwardly from the points of the pins as may be desired. The material to be gathered up or collected is pierced by the said pins and when they are 20 full may be carried to some central point and placed in a pile or heap, the said material being stripped from the said pins by causing relative movement between the cleaner or stripper 12 and the pins 30 so as 25 to cause these parts to occupy relative positions substantially as shown in Fig. 4 of the drawings in which the cleaner or stripper plate 12 is located adjacent to the outer ends of the pins.

30 When the part 12 is moved into the position shown in Fig. 4 the links 15 pass into radial slots 21 in the base 2 as shown. It is immaterial whether this relative position be brought about by causing movement of 35 the plate or the pins.

Having thus described my invention, I claim:—

1. In a device of the character described, 40 the combination of a group of pointed devices which decrease in height from

the center toward the outer edge of the group, a base or support to which the said pointed devices are secured, a handle secured to the said base or support, a bent plate having perforations through which 45 the said pointed devices pass, the said plate being of cone shape, a longitudinally movable member supported upon the said handle and means having connection with the said longitudinally movable member and 50 the said cone-shaped plate whereby movement of the latter is caused by movement of the said member on the said handle.

2. In a device of the character described, 55 the combination of a handle having a plate secured to the lower end thereof, said plate having radially extending slots therein, piercing fingers or prongs secured to said plate, a stripping plate having perforations 60 therein through which the said piercing fingers or prongs extend, a sleeve slidably secured upon said handle, links connected to the lower edge of said sleeve and to the outer edge of said stripping plate, the said links causing longitudinal movement of the 65 said stripping plate on the said piercing fingers or prongs as the said sleeve is moved back and forth upon the handle and the said links moving in and out of the said slots, and a flat spring secured upon the side of said 70 handle and adapted to exert pressure against the said sleeve for the purpose stated.

In testimony that I claim the foregoing 75 as my invention, I have hereunto signed my name this 21st day of February, A. D. 1911.

PERCY L. MARTIN.
In the presence of—
E. G. COURTNEY,
L. P. BLACKBURN.
